UNITED STATES PATENT OFFICE

138,764

DESIGN FOR WALLPAPER BORDER OR SIMILAR ARTICLE

William Burton, Chicago, Ill., assignor to United Wall Paper Factories, Inc., Chicago, Ill., a corporation of Delaware

Application June 19, 1944, Serial No. 114,059

Term of patent 7 years

(CL. D59—10)

To all whom it may concern:

Be it known that I, William Burton, a citizen of the United States, residing at Chicago, in the county of Cook and State of Illinois, have invented a new, original, and ornamental Design for Wallpaper Border or Similar Article, of which the following is a specification, reference being had to the accompanying drawing, forming a part thereof.

In the drawing—

The figure is a plan view of a wallpaper border showing my new design.

I claim:

The ornamental design for wallpaper border or similar article, as shown.

WILLIAM BURTON.
